Attorney, Agent, or Firm—Russell W. Warnock; Alan A. Csontos[57] **CLAIM**

The ornamental design for a tire, as shown and described.

DESCRIPTION

FIG. 1 is a perspective view of a tire showing my our design, it being understood that the tread pattern is repeated uniformly throughout the circumference thereof;

FIG. 2 is a front elevational view of the tire shown in FIG. 1;

FIG. 3 is a side elevational view of the tire shown in FIG. 1; and,

FIG. 4 is an enlarged front elevational view of a portion of the tire shown in FIG. 1.
